UNITED STATES PATENT OFFICE.

EDWIN J. CLAYTON, OF PHILADELPHIA, PENNSYLVANIA.

NON-REFILLING ATTACHMENT FOR BOTTLES.

No. 870,932.

Specification of Letters Patent.

Patented Nov. 12, 1907.

Application filed April 6, 1907. Serial No. 366,768.

To all whom it may concern:

Be it known that I, EDWIN J. CLAYTON, a citizen of the United States, residing at Philadelphia, in the county of Philadelphia and State of Pennsylvania, 5 have invented a certain new and useful Non-Refilling Attachment for Bottles, of which the following is a specification, reference being had therein to the accompanying drawing.

This invention relates to attachments for bottles by 10 means of which bottles are rendered non-refillable, so that while the bottles to which the attachments are applied may be easily emptied by pouring out the contents in the usual way, they cannot afterwards be refilled without destroying the attachment or its identity, thus enabling the purchaser of any portion of the 15 contents of the bottle to know with certainty whether or not the same has been tampered with. In this way not only is the purchaser or consumer assured of getting what he desires, but the producer is also protected in getting his goods to the purchasing public 20 and consumer.

With the above and other objects in view, the invention consists in the novel construction, combination and arrangement herein fully described and 25 claimed.

In the accompanying drawings:—Figure 1 is a perspective view of the attachment of this invention. Fig. 2 is a vertical section through the neck of a bottle showing the attachment in place therein. Fig. 3 is a 30 horizontal section through the attachment on the line 3—3 of Fig. 2.

Under the preferred embodiment of this invention a bottle having a straight neck of uniform size throughout its whole length is used so that after the bottle has 35 been filled with liquid, the attachment hereinafter described may be introduced through the mouth of the bottle and pressed by a suitable implement down into the lower part of the neck in the position illustrated in the drawings, wherein a neck of the character described is shown and designated 1.

The attachment embodies a combined valve seat and retainer composed of two pieces, a circular body or annulus 2 of some stiff material such as metal or hard rubber, and a flexible or resilient ring 3 which 45 encircles the valve seat formed by the annulus or circular body 2. Preferably the body 2 has a grooved periphery as shown at 4 thereby forming what may be termed upper and lower flanges 5 and 6. The ring 3 acts as a retainer for holding the attachment as a whole 50 securely in the neck of the bottle in the manner indicated in Fig. 2. A ball valve 7 sets on the valve seat and cooperates therewith to cut off the flow of liquid

when the bottle is not inverted to pour out the contents thereof. At the same time the valve readily unseats itself when the bottle is inverted and permits 55 the contents to be readily poured out.

To hold the valve in place and insure the proper operation thereof, a cage is connected with the combined valve seat and retainer, the said cage comprising the cage bars 8 and a cap 9 arranged at a suitable 60 distance from the seat to admit of the necessary play of the valve in unseating. This cap is preferably concavo-convex with the convex side uppermost and the diameter of the cap is slightly less than the internal size of the bottle neck so that a tubular instrument may be used to press the attachment into place, the applied pressure being thereby directed against the retainer ring 3 thus carrying the attachment into place without in any way injuring the same. To facilitate the outflow of the liquid, the cap is perforated as shown at 10 and this is preferably done by punching portions of the cap upward without removing any of the material thereof, thus leaving protecting overhanging lips which cover the openings and prevent a piece of wire or other implement from being 70 inserted in the openings in an attempt to extract the attachment.

The bars 8 project across or partly across the periphery of the body or annulus 2 and are received in notches 11 provided therefor in the upper flange 5, 80 while the elastic ring or retainer 3 binds said bars in place, thus holding all parts of the attachment together. The bars 8 may be in the form of wickets with the central connecting portions thereof extending diametrically across the lower side of the cap 9 85 and united thereto by solder or in any convenient manner, as may be preferred. The device as a whole is preferably made very light and fragile so that any attempt to remove the same from the bottle will result in the destruction or mutilation of the attachment to an extent which will be readily observable 90 by any one. The only way in which the bottle can be refilled is by removing the attachment and thereby destroying it, and, after then refilling the bottle, putting a new attachment of the same kind into the neck 95 of the bottle by an instrument made especially for the purpose. Therefore, after the bottle has been emptied, it must either be thrown away or returned to the manufacturer of the goods to be refilled.

I claim:—

1. A non-refilling attachment for bottles embodying a valve seat, a valve cage, a valve cooperating with said seat and mounted in the cage, and a flexible ring encircling the valve seat and serving to hold the cage and seat together

100

and also serving as a retainer for holding the device as a whole in the bottle neck.

2. A non-refilling attachment for bottles embodying a combined valve seat and retainer, a valve cage connected with said seat and comprising a cap having perforations and overlying projections, and a valve coöperating with said seat and mounted within the cage.

3. A non-refilling attachment for bottles embodying a ring of concavo-convex shape in cross section, a valve cage having the bars thereof projecting across the concaved

periphery of said ring, a flexible band encircling the ring and the projecting ends of the cage bars, and a valve coöperating with said ring and mounted within the cage.

In testimony whereof I affix my signature in presence of two witnesses.

EDWIN J. CLAYTON.
